RATCHET TOOL

Application filed January 23, 1930. Serial No. 422,944.

This invention relates to tools, and more particularly to screw drivers having a ratchet mechanism for positively rotating the same in either direction.

5 My invention has for an object to provide a supplemental handle carried by the tool which constitutes an actuating means for the tool for rotation in either direction.

A further object of the invention is to provide a construction whereby positive rotation may be imparted to the tool in either direction after merely pivoting the supplemental handle to either side of the tool.

The main feature of the invention resides 15 in the formation of the supplemental handle so that the said handle constitutes the pawl or actuating member of the ratchet mechanism for permitting positive rotation in either direction.

20 Another object of the invention is to provide a means for holding the supplemental handle in inoperative position when desired to use the tool as an ordinary screw driver.

Other and further objects and advantages 25 of the invention will be hereinafter set forth and the novel features thereof defined by the appended claims.

In the drawings:

Fig. 1 is a vertical elevation of the tool 30 showing the supplemental handle in inoperative position;

Fig. 2 is a vertical elevation at right angles to the position in Fig. 1, the dotted lines showing the supplemental handle in operative position;

Fig. 3 is a fragmentary, vertical, sectional view taken on line 3—3 of Fig. 2;

Fig. 4 is a fragmentary, horizontal, sectional view taken on line 4—4 of Fig. 3, the 40 supplemental handle being shown in full lines for imparting rotation in one direction and in dotted lines for imparting rotation in the opposite direction;

Fig. 5 is a detail perspective view of one 45 form of the ratchet member to be engaged by the supplemental handle; and

Fig. 6 is a modified form of ratchet member.

Like numerals refer to like parts in the 50 several figures of the drawings, in which 1

denotes a bit stock or handle having a screw driver shank 2 or other tool inserted therein. The shank is preferably formed flat on at least two sides for positively engaging a ratchet member 3 slidable thereon, the aperture 4 through the said ratchet member being correspondingly shaped with respect to the shank 2. The ratchet member 3 is preferably secured in a cylindrical casing 5 which is spun or crimped over at each side, as at 55 6, to retain the said ratchet member therein. The internal diameter of the cylindrical casing is sufficiently great to permit free rotation of the casing with respect to the ratchet member 3. If desired, washers 7 may be placed on each side of the ratchet member between the said ratchet member and the spun edges of the casing.

The ratchet member is provided with transverse slots or channels 8 which are adapted 70 to be engaged by the supplemental U-shaped handle 9 pivoted in the casing 5 by means of the inwardly extending end portions 10 and 11 adapted to fit in the apertures 12 formed diametrically opposite each other in 75 the casing. The end portion 10 terminates flush with the interior surface of the casing, whereas the end portion 11 is formed with a projection 13 having an inclined face 14 and adapted to extend into the grooves 8 formed 80 in the ratchet member 3.

Obviously, a positive rotation will be imparted to the tool in one direction by pivoting the supplemental handle toward one side of the tool, as shown by the full lines in Fig. 85 4, and rotating the said supplemental handle in that direction, the inclined face of the projection 13 causing the supplemental handle to spread apart and ride over the ratchet member when the handle is rotated in the opposite direction. The supplemental handle is sufficiently resilient to permit this spreading action. Pivoting the supplemental handle in the opposite direction, as shown in dotted lines in Fig. 4, will dispose the inclined face 14 oppositely with respect to the ratchet member 3 and positive rotation may then be effected in the opposite direction from that previously mentioned. During operation of the tool, one hand of the operator 90 95 100

steadies the tool by means of the stock or handle 1, while the said tool is actuated by the supplemental handle 9 manipulated by the other hand.

5 The handle 1 is preferably formed flat on two sides to permit the U-shaped supplemental handle 9 to be swung into alignment with the axis of the tool and seated in a groove 15 where it is caused to be held in inoperative position under the influence of a spring 16 surrounding the tool shank 2 between the end of the handle 1 and the ratchet mechanism. Obviously, any suitable means for securing the supplemental handle in inoperative position might be employed, and, therefore, I do not wish to be limited to the particular groove and spring means as shown in the drawings.

10 The shank 2 of the tool is preferably formed uniformly in shape well down to the working end to permit the supplemental handle and ratchet mechanism to be positioned at any point along the shank during operation of the tool by the same, in order to obtain the 15 desired purchase. This also permits the supplemental handle to be swung downwardly and over to the opposite side of the tool shank for reversing the positive action of the said supplemental handle.

15 The modified form of ratchet member 3' as shown in Fig. 6, formed with the aperture 4' in the center thereof to fit the tool shank and having spaced apertures 8' extending into the same around the periphery thereof, may be employed in lieu of the construction shown in Fig. 5.

20 The supplemental handle may be entirely removed from the tool when desired by merely spreading the same apart and causing the inwardly extending end portions to be withdrawn from the ratchet mechanism.

25 The operation of my invention is obvious from the foregoing description and may be briefly summarized as follows:

30 The supplemental handle 9 is disengaged from the groove formed in the tool handle 1 and pivoted to one side of the tool, whereupon the tool is placed on the work and steadied by the handle 1 while actuated by the supplemental handle which permits of rotation of the tool in one direction in short or long strokes as desired by virtue of the ratchet mechanism. To impart positive rotation in the opposite direction, it is only necessary 35 to pivot the supplemental handle to the other side of the tool. By pivoting the supplemental handle into alignment with the axis of the tool, and seating the same in the groove extending across the top of the handle, the 40 tool may be used in the ordinary manner, or the supplemental handle may be entirely removed if desired.

45 The supplemental handle may be used merely as a guide for the tool as well as for an actuating means for the tool. For example,

50 with the supplemental handle disposed as shown by the dotted lines in Fig. 2, the end of the tool may be engaged with the screw, bolt, or the like, and the tool manipulated in the ordinary manner by means of the handle 1 the supplemental handle being held in one position on the particular side of the tool which permits free operation of the same by the tool handle 1, the inclined face 55 14 riding over the ratchet member. Such use of the supplemental handle as a guide for the tool has considerable merit, as it is often difficult to keep a screw driver on the screw head during manipulation of the screw driver.

55 While the specific details of construction have been herein shown and described, the invention is not confined thereto as changes and alterations may be made without departing from the spirit thereof as defined by the 60 appended claims.

Having thus described my invention, what I claim as new and desire to secure by Letters Patent is:

65 1. A ratchet tool of the class described comprising a handle, a tool carried thereby, ratchet means, and a supplemental handle constituting a reversible pawl for said ratchet means for rotating said tool in either direction.

70 2. A ratchet tool of the class described comprising a handle, a tool carried thereby, ratchet means slidable on said tool, said ratchet means comprising an enclosing casing having a rotatable ratchet member positioned therein, and a supplemental handle pivoted to said casing and constituting a pawl for said ratchet means.

75 3. A ratchet tool of the class described comprising a handle, a tool carried thereby, ratchet means longitudinally adjustable on said tool, said ratchet means including a supplemental handle constituting a pawl for said ratchet means, and means for retaining said supplemental handle in inoperative position.

80 4. A ratchet tool of the class described comprising a handle, a tool carried thereby, ratchet means slidable on said tool, said ratchet means including a casing, a ratchet member rotatably carried thereby and having pawl engaging means, a supplemental handle having inwardly extending end portions engaging the said casing for pivotally connecting the said supplemental handle thereto, and a projection having an inclined face formed on one of said end portions and constituting a pawl for said ratchet member, said supplemental handle being adapted to 85 permit positive rotation of the said tool in one direction when the supplemental handle is pivoted to one side of said tool and in the opposite direction when pivoted to the other side of said tool.

90 5. A ratchet tool of the class described com-

prising a handle, a tool carried thereby, and ratchet means longitudinally slidable on said tool, said ratchet means including a supplemental handle, means for pivoting said supplemental handle, and an integral extension on said pivoting means, said extension constituting a reversible pawl for permitting positive rotation of the tool in either direction by the said supplemental handle incident to pivoting of the same.

6. A ratchet tool of the class described comprising a handle having a transverse groove in one end thereof, a tool carried by said handle, ratchet means carried by the said tool for permitting rotation of the tool in either direction, said ratchet means including a pivotal U-shaped supplemental handle adapted to pivot to extend in alignment with the axis of the tool and seat in said transverse groove when in inoperative position, and means intermediate the first mentioned handle and ratchet means for retaining the supplemental handle in said inoperative position.

25 7. A ratchet tool of the class described comprising a handle having a transverse groove in one end thereof, a tool carried by said handle, ratchet means carried by the said tool for permitting rotation of the tool in either direction, said ratchet means including a pivotal U-shaped supplemental handle adapted to pivot to extend in alignment with the axis of the tool and seat in said transverse groove when in inoperative position, and means intermediate the first mentioned handle and ratchet means for retaining the supplemental handle in said inoperative position, said means constituting a helical spring.

40 8. A ratchet tool of the class described comprising a handle, a tool extending therefrom, ratchet means longitudinally adjustable on said tool, said ratchet means comprising a cylindrical casing, a ratchet member rotatable in said casing, said ratchet member positively engaging said tool, a resilient U-shaped supplemental handle pivoted to said casing at diametrically opposite points, and a projection formed on said supplemental handle in axial alignment with said pivot points, said projection constituting a reversible pawl for said ratchet means.

In testimony whereof I affix my signature.

WILLIAM H. ARBOGAST.
